UNITED STATES PATENT OFFICE.

ERNEST T. KINDT, OF CLEVELAND, OHIO.

DOWEL PIN.

Application filed April 7, 1922. Serial No. 550,548.

To all whom it may concern:

Be it known that I, ERNEST T. KINDT, a citizen of the United States, and a resident of Cleveland, county of Cuyahoga and State 5 of Ohio, have invented a new and useful Improvement in Dowel Pins, of which the following is a specification, the principle of the invention being herein explained and the best mode in which I have contemplated applying that principle, so as to distinguish it 10 from other inventions.

The present invention relates to metal dowel pins and means for inserting the pins properly in place, and more particularly, relates to the construction of the pins themselves and to the construction of a suitable wrench for manipulating the pins. These present pins are adapted to be screwed into the wooden parts which are to be held together 15 and are so arranged that a snug fit is obtained between the two pins when they are in place in the wooden parts. To the accomplishment of the foregoing and related ends, 20 said invention, then, consists of the means hereinafter fully described and particularly 25 pointed out in the claims.

The annexed drawing and the following description set forth in detail certain mechanism embodying the invention, such 30 closed means constituting however, but one of various mechanical forms in which the principle of the invention may be used.

In said annexed drawing:—

Fig. 1 is a sectional view through both 35 male and female pins installed in a pattern; Fig. 2 is an elevational view of the male pin; Fig. 3 is an end view of the male pin; Fig. 4 is a cross section of the female pin; and Fig. 5 is a plan view of the wrench with 40 one end in section to show the socket construction.

The present dowel pins comprise complementary male and female members 1 and 2 which are best shown in Fig. 1, each member 45 having a screw threaded shank 3 with a thin flange 4 at its upper surface adapted to be screwed flush with the surface of the wooden pattern 5 in which the member is to be placed. The male member 1 of the pins is 50 provided with a pin 6 extending from the flange 4, which pin is cylindrical for a short distance 7 above the flange and is then tapered ending in a rounded nose 8. The sides are cut away as at 9 to form a squared portion 55 for engagement by a wrench or the like. The female member 2 of the pins is likewise

provided with the screw threaded exterior 3 and the thin flange 4 at its upper end but is hollowed out to form a socket 10 for the pin on the male member. This socket is provided with four V-shaped grooves 11 adapted to give the effect of a square opening therein although the cylindrical part 10 of the socket is of such size as to snugly receive the circular portion 6 of the pin on the male 60 member.

In using the present dowel pins it is most satisfactory to secure the parts of the pattern or core-box 5 together and to drill a hole 12 through both parts of the pattern or core-box, and then to separate the same and insert the male and female members of the dowel pins in the apertures in the pattern or core-box. If more than one dowel pin is to be used, the core-box will again be put together with one set of pins in place and the next set of holes made and the pins inserted 70 in the same manner as the first set.

In order to allow these dowel pins to be screwed into place into the wooden patterns, 80 the male member has a portion of the extending pins squared so as to be engaged by the squared socket 13 in one end of a wrench 14, while the female member of the pin is provided with the grooves forming the equivalent of 85 a squared socket in the female member to receive the squared end 15 of the wrench. This allows both members of the dowel pin to be screwed into place instead of being hammered or driven in, as is the usual practice. 90

When either a screw threaded pin or one having a roughened exterior, is driven into place in the wooden pattern, the wood is crushed and the pin is very liable to be slightly tilted, and if the pin is for any reason removed, it cannot be again inserted in the same hole because the crushing of the wood fibers and the tearing out of the same upon removal, increases the size of the hole sufficiently to make the pin loose upon re-insertion.

With the present dowel pins, each member is screwed into place and the thin flange which is at the upper end of the member may be secured flush with the surface of the 100 wood and the pin is always accurately centered and may be easily removed and re-centered if necessary. The small wrench 14 as shown, has the squared socket 13 at one end which has a cylindrical portion 17 adjacent 110 the end of the wrench so as to fit around the cylindrical portion of the pin of the male

member, while the other end of the wrench has the squared projection 15 adapted to fit in and engage with the grooves in the socket of the female member.

5 The advantages of the present pin are thought to be clear, inasmuch as they allow the pins to be screwed into place and thus removed when desired, and also allowing the pins to be tightened in their sockets by 10 merely screwing them down if they become loosened. Further advantage is found in the fact that while both the female member and the male member are provided with squared 15 portions, they are also provided with cylindrical portions which allow the two members to fit snugly together so as to prevent the pattern parts from moving out of alignment, and thus they retain the advantages of the old forms of pins while making it possible 20 to screw these pins into position.

Other modes of applying the principle of my invention may be employed instead of the one explained, change being mad as regards the mechanism herein disclosed, provided 25 the means stated by any of the following claims or the equivalent of such stated means be employed.

I therefore particularly point out and distinctly claim as my invention:—

30 1. In dowel pin construction the combination of complementary male and female pins, each provided with a screw threaded shank having a thin upper flange and means for engagement with a wrench to allow such pins to be screwed into position.

35 2. In dowel pin construction the combination of complementary male and female pins, each provided with a screw threaded shank having a thin upper flange, and complementary pin and socket construction formed for engagement with a wrench to allow the pins to be screwed into position.

40 3. In dowel pin construction the combination of complementary male and female pins, each provided with a screw threaded shank having a thin upper flange, the male member having a pin portion with a squared portion, the female member having a socket with grooves, such squared end and socket being adapted for engagement with a wrench to allow said pins to be screwed into position.

45 4. In dowel pin construction a male mem-

ber having a screw threaded shank portion provided with a thin flange and provided 55 with a tapered pin extending centrally from said flange, said pin being squared for engagement with a socket wrench to allow said member to be screwed into position.

5. In dowel pin construction a male member having a screw threaded shank portion provided with a thin flange and provided 60 with a tapered pin extending centrally from said flange, said pin being cylindrical for a short distance above said flange and then 65 being cut away to form a squared portion ending in a rounded end to allow said member to be engaged by a socket wrench to screw said pin into position.

6. In dowel pin construction, a female 70 member having a screw threaded shank provided with a thin flange, said shank being hollow to provide a socket for the complementary male member, such socket being 75 grooved to provide a squared socket to receive a squared wrench end to allow said member to be screwed into position.

7. In dowel pin construction, a female member having a screw threaded shank provided with a thin flange, said shank being 80 hollow to provide a socket for the complementary male member, such socket being provided with a plurality of spaced V 85 grooves so arranged as to leave a cylindrical bore to snugly receive the male member and to form a squared socket to receive the squared end of a wrench to allow the member to be screwed into position.

8. In dowel pin construction, the combination of male and female members, each 90 comprising a screw threaded shank portion having a thin flange, said male member having a pin extending centrally from said flange, said pin being cylindrical for a short 95 distance above said flange and then tapering to a rounded point, the sides of the pin being cut away to form a squared portion for engagement with a socket wrench, said female member having its shank provided with a cylindrical bore adapted to snugly receive 100 such cylindrical portion of said male pin, said bore being provided with V grooves adapted to form a squared socket to receive the squared end of a wrench.

Signed by me this 4th day of April, 1922.

ERNEST T. KINDT.
